US0D1099258S

(12) **United States Design Patent** (10) **Patent No.:** **US D1,099,258 S**
(45) **Date of Patent:** **** Oct. 21, 2025**

(54) **SCALLOP HARVESTING BAG**

(71) Applicant: **Pluck Em Dive Sports LLC**, Clermont, FL (US)

(72) Inventor: **Daniel Lee Davidson**, Clermont, FL (US)

(73) Assignee: **Pluck Em Dive Sports LLC**, Clermont, FL (US)

(**) Term: **15 Years**

(21) Appl. No.: **29/911,556**

(22) Filed: **Sep. 5, 2023**

Related U.S. Application Data

(63) Continuation of application No. 16/949,021, filed on Oct. 9, 2020, now Pat. No. 11,779,002.

(57) **CLAIM**

The ornamental design for a scallop harvesting bag, as shown and described.

DESCRIPTION

FIG. 1 is a front perspective view of the scallop harvesting bag showing my new design;

FIG. 2 is a front elevation view thereof, the rear, the rear elevation view being a mirror image thereof;

FIG. 3 is a top plan view thereof;

FIG. 4 is a bottom plan view thereof; and

FIG. 5 is a left side elevation view thereof;

FIG. 6 is a right side elevation view thereof;

FIG. 7 is a cross sectional view taken along line 7-7 of FIG. 3; and,

FIG. 8 is perspective view of the scallop harvesting bag shown in use.

The dashed lines in the drawings illustrate portions of the scallop harvesting bag that form no part of the claim.

The dashed-dot-dash lines in the drawings of FIG. 8 illustrate environment that forms no part of the claim.

1 Claim, 6 Drawing Sheets
